J. KOVÁCS.
AERIAL BOMB.
APPLICATION FILED AUG. 9, 1916.

Patented Mar. 13, 1917.

Inventor

JOSEPH KOVÁCS

Attorney

UNITED STATES PATENT OFFICE.

JOSEPH KOVÁCS, OF FORDS, NEW JERSEY.

AERIAL BOMB.

1,218,871.

Specification of Letters Patent. Patented Mar. 13, 1917.

Application filed August 9, 1916. Serial No. 113,971.

To all whom it may concern:

Be it known that I, JOSEPH KOVÁCS, a citizen of the United States, residing at Fords, in the county of Middlesex and State of New Jersey, have invented certain new and useful Improvements in Aerial Bombs, of which the following is a specification, reference being had to the accompanying drawings.

10 This invention relates to projectiles and particularly to bombs designed to be dropped by aviators or thrown by hand as hand grenades.

15 The general object of this invention is the provision of a very simple bomb which is formed in sections so that it may be easily loaded or the load removed and further to provide an improved form of detonator or fuse whereby the bomb may be exploded.

20 A further object is to provide a detonator so constructed that the detonating cap may be readily put in place or removed and is held securely in place against accidental shifting when the bomb is ready for firing.

25 Further objects will appear in the course of the following description.

My invention is illustrated in the accompanying drawings, wherein,

Figure 1 is a top plan view of a bomb 30 constructed in accordance with my invention;

Fig. 2 is a side elevation of the same, the wall of the bomb being broken away and being partly shown in section;

35 Fig. 3 is a section on the line 3—3 of Fig. 2; and

Fig. 4 is an elevation of the firing pin.

Referring to these figures it will be seen that my improved projectile comprises two 40 semispherical sections designated respectively 10 and 11. At their ends these sections are reduced in thickness and coaxially screw-threaded as at 12 for detachable engagement with each other. It will be seen 45 that the section 10 is somewhat less than a semisphere and the section 11 somewhat greater than a semisphere. Formed in the walls of the projectile are the passages 13 and upon the walls are the outwardly projecting 50 interiorly screw-threaded sockets 14, the interior diameter of each of these sockets being greater than the diameter of the corresponding passage 18. The passage 13 has a diameter equal to that of the detonating 55 cap 15, while the head of this cap bears against the seat or shoulder 16 formed at

the junction of the passage 13 with the interior of the socket 14. Having screw-threaded engagement with the socket 14 is the supporting plug 17 which is tubular in 60 form and exteriorly screw-threaded and provided with a relatively enlarged head 18. This plug is adapted to engage the screw threads of the socket 14. The bore of the screw-threaded body of the plug is larger 65 than the bore of the head 18 and passing through the bore of the head 18 is the shank 19 of a firing pin, this firing pin having a head 20 and at its inner end a head 21 which is pointed so as to pierce or dent the cap 15. 70 This head 21 is formed with the lateral wings 22 which engage with grooves 23 formed in the wall of the socket. The firing pin may be held projected by means of a spring surrounding the shank 19 if desired, 75 or no spring need be used. In Fig. 1, I have illustrated a spring 24 holding the firing pin retracted from the detonating cap.

The section 11 is also provided around its circumference and adjacent the open end of 80 the section with a plurality of sockets 14, each of these sockets having engaged therewith a firing plug 17 within which operates the firing pin 19 as previously described. The detonating caps extend into the body 85 of the projectile or bomb.

It will be seen that the bomb constructed in accordance with my invention if thrown or dropped will be practically certain to land upon one at least of the several firing 90 pins which will cause the explosion of the cap and the consequent explosion of the charge and the bursting of the bomb. The particular advantage incident to the construction of the detonating plug and pin is 95 that by this construction it is an easy matter to insert or remove the detonating caps 15. In all devices heretofore provided for this purpose, as far as I know, it has been difficult to insert the detonating caps or primers 100 in place. With my device it is only necessary to unscrew the plug 17 and then insert the cap 15 in the relatively shallow socket 14 until it is seated against the shoulder 16. The plug is then replaced and the end of the 105 shank of the plug bears against the detonating cap as shown clearly in Fig. 2, and holds the detonating cap locked in position so that it cannot shift, even when the firing pin is retracted. While I have illustrated 110 this particular construction of firing plug and pin as applied to a particular form of

bomb, I wish it understood that it might be applied to other forms of projectiles.

Having described my invention, what I claim is:

- 5 An explosive bomb of the character described including an ovoidal hollow body formed with two coacting sections having screw-threaded engagement with each other, the body being formed with a plurality of
- 10 openings extending at spaced distances in a plane intersecting the middle of the body and disposed also at the ends of the body, each of said openings being formed with a projecting wall interiorly screw-threaded
- 15 and constituting a socket larger in diameter than the diameter of the corresponding pas-

sage, a firing plug for each socket having a relatively large head and having screw-threaded engagement with said socket and adapted to bear at its inner end against the 20 head of the detonator and hold it in place, and a firing pin slidably mounted in the head of the plug and having an enlarged head at its outer end and an enlarged head at its inner end.

25

In testimony whereof I hereunto affix my signature in the presence of two witnesses.

JOSEPH KOVÁCS.
